TRI-HULL SAILING BOAT

Dudley F. Miller, Jr., 25 Hill Drive,
Ross, Calif. 94957

Filed Dec. 29, 1971, Ser. No. 213,796

Term of patent 14 years

Int. Cl. D12—06

U.S. Cl. D71—1 BB

FIG. 1

FIG. 1 is a right side view in elevation of a tri-hull sailing boat showing the features of my new design which is the same as a left side view;

FIG. 2 is a front view in elevation of the same; and

FIG. 3 is a top view of the same.

I claim:

The ornamental design for a tri-hull sailing boat, substantially as shown and described.
